UNITED STATES PATENT OFFICE.

JOHN D. BROWNE, OF SPRINGFIELD, MASSACHUSETTS.

MAIL-BOX-ELEVATING APPARATUS.

1,148,951.

Specification of Letters Patent.

Patented Aug. 3, 1915.

Application filed August 15, 1914. Serial No. 856,887.

To all whom it may concern:

Be it known that I, JOHN D. BROWNE, a citizen of the United States of America, and resident of Springfield, in the county of 5 Hampden and State of Massachusetts, have invented certain new and useful Improvements in Mail-Box-Elevating Apparatus, of which the following is a full, clear, and exact description.

10 This invention relates to improvements in an apparatus for the elevation of mail boxes from the corridor or street floor of an apartment building to floors thereabove for convenience of the tenant.

15 The invention is described in conjunction with the accompanying drawings and is set forth in the claims.

In the drawings:—Figure 1 is a front elevation, somewhat in the nature of a diagram, indicating the general arrangement 20 of installation of the apparatus; Fig. 2 is a front elevation on a somewhat larger scale, showing the principal novel features; Figs. 3 and 4 are transverse sectional views taken 25 respectively on lines 3—3 and 4—4 of Fig. 2.

In the drawings, A represents by dotted lines a chute or well leading from the corridor vertically to a floor above, such chutes being multiplied for different floors or 30 apartments thereon. Suitably located on the wall in the hallway or vestibule of a given floor is a motor B having a shaft C on which is a clutch member D; and on the motor shaft is a winding spool E which is 35 slidable endwise along the shaft and provided with a clutch member F which is cooperative with the motor shaft clutch member D. The spool is provided with an elongated hub G having an annular groove α 40 therein, in which groove a collar J is engaged, which collar is provided with a forwardly extending arm b and with a vertical rigid extension d, located in the line of the chute which latter at its upper end is open, 45 at its front, so that the mail box when elevated is accessible.

Upon the frame or bracket in which the motor and the spool are mounted is a lug M having a notch f in which the arm b of the 50 collar has a latching or locking engagement to hold the spool in clutch with the motor. With the collar or suitable extensions thereof springs g g are connected, the stress of which is such as to draw the spool endwise 55 out of clutch with the motor for the discontinuance of the winding action and the ele-

vation of the mail box after the same shall have reached the floor of its destination.

The mail box O is fitted and movable in the chute A, and by the cord, chain, or other 60 flexible connection, i, in winding engagement is raised and permitted to be lowered.

When the mail box reaches its proper height on a given floor so that the contents placed therein by the letter carrier in the 65 corridor or ground floor is accessible to a tenant occupying a given upper floor, the abutment k thereon strikes the extension d of the collar arm b, swinging the latter out from its locking engagement in the notch 70 f of the lug M, whereupon the springs become effective for drawing the spool out of clutch with the motor shaft for terminating the further winding and elevation.

The spool has a ratchet wheel p thereon 75 with which a pawl or click q engages,—this provision preventing the mail box from descending by gravity after the discontinuance of the elevating rotation of the spool. With the other end flange of 80 the spool a pivoted brake member R co-acts, the same being pivoted at m and held normally free from its braking engagement by the spring n which holds the brake from frictional engagement with the rim of the 85 flange comprised in the clutch member F and against the stop t. The brake member has its location such that it may coact, by being manually forced, against the flange, like clutch member F when the latter is 90 out of clutch.

After the elevation of the box and the withdrawal of the contents thereof, the pawl may be manually disengaged, leaving the box free to descend to the ground floor 95 in proper place to receive further mail deliverable thereinto by the letter carrier.

As manifest, the descent of the mail box may be checked or regulated by the person letting it down through the operation of 100 the brake.

I claim:—

1. In an apparatus of the character described, in combination with a vertical chute, a motor having a shaft, provided 105 with a clutch member, a winding spool slidable on the shaft having a clutch member, means exerting a stress to draw the spool out of clutch, a hub on the spool provided with an annular groove, a collar engaged in the groove and provided with an arm made with an extension, a bracket pro-

vided with a lug having a notch therein in which said arm has a latching engagement, a mail box to move in the chute having a flexible connection in winding engagement 5 with the spool, and adapted upon its elevation to a given height to abut against the extension of said arm for throwing the arm out of its latching engagement with said notched lug, leaving the spool free to be 10 withdrawn from its clutching engagement with the motor shaft.

2. In an apparatus of the character described, in combination with a vertical chute, a motor having a shaft provided 15 with a clutch member, a winding spool slidably movable on the shaft, provided with a flange-like clutch member, to coact with the motor shaft clutch member, said spool being also provided with a ratchet 20 wheel and having a hub made with an an-

nular groove, a collar engaged in the groove of the hub adapted to swing and also to bodily move with the spool, a stationary lug having a notch therein in which the collar extension has a latching engagement, a mail 25 box to move in the chute having a flexible connection in winding engagement with the spool, and adapted to throw the extension of the collar out of engagement with said notched lug, spring means for drawing the 30 spool when released out of clutch, a pawl coacting with the said ratchet wheel, and a brake adapted to coact with the flange-like clutch member of the spool.

Signed by me at Springfield, Mass., in 35 presence of two subscribing witnesses.

JOHN D. BROWNE.
